UNITED STATES PATENT OFFICE.

HERBERT McCORNACK, OF WEST CHESTER, PENNSYLVANIA.

INTERNAL-COMBUSTION ENGINE.

1,036,503.

Specification of Letters Patent. Patented Aug. 20, 1912.

Application filed August 21, 1906. Serial No. 331,514.

To all whom it may concern:

Be it known that I, HERBERT McCORNACK, a citizen of the United States, residing at West Chester, in the county of Chester and State of Pennsylvania, have invented a new and useful Improvement in Internal-Combustion Engines, of which the following is a specification.

This invention has reference to that class of internal combustion engines in which a charge of gaseous fuel is supplied to the cylinder for every two strokes of the piston and which are usually referred to as two-cycle engines, and relates more especially to that class of these engines in which the fuel inlet port of the cylinder is opened during the last portion of the power stroke of the piston, shortly after the exhaust port has been opened, so that the fuel inlet port and the exhaust port are open at the same time.

The objects of the invention are to provide simple and efficient means for admitting the fuel to the cylinder and for scavenging the latter and freeing it as completely as possible from the spent gases.

To that end the fuel admission devices are so constructed that the incoming fresh fuel is distributed around the inner surface of the cylinder in an annular layer as it enters the cylinder, envelops the spent gases contained in the cylinder and drives these gases inwardly toward an axial exhaust port.

In the accompanying drawings: Figure 1 is a sectional elevation of an engine embodying my invention. Fig. 2 is a sectional elevation of the piston, on an enlarged scale. Fig. 3 is a horizontal section in line 3-3, Fig. 2.

Like letters of reference refer to like parts in the several figures.

A represents the cylinder of an upright engine provided with a spark or igniter *a* of any suitable construction and having, if desired, a cooling jacket *b*.

B represents the piston, C the compression chamber upon which the cylinder is mounted, D the crank rotating in said chamber and E the rod which connects the crank with the piston.

f represents the fuel supply port for the compression chamber which is arranged in the lower portion of the cylinder, at one side thereof, and is uncovered by the piston when the latter is near the end of its return

stroke, the gas in the chamber being compressed by the piston during the power stroke.

g represents the fuel inlet passage of the cylinder arranged at one side thereof and connecting at its lower end with the compression chamber, while it opens at its upper end inwardly through the wall of the cylinder.

h represents the cylinder exhaust port which is arranged, as shown, in the wall of the cylinder above the fuel supply port *f* and opposite the fuel inlet passage *g*.

The piston is provided in its upper portion with an exhaust port *i* which has its inlet arranged axially in the top of the piston and which extends downwardly in the piston and then to one side, so that its outlet registers with the cylinder exhaust port *h* when the piston has arrived near the end of its power stroke.

k represents the fuel inlet port of the piston which has the form of a recess formed in the outer side of the piston so as to register with the upper end of the fuel inlet passage *g* of the cylinder when the piston has arrived near the end of its power stroke. This external inlet port of the piston is in communication with an annular distributing chamber *O* which is formed in the piston above the port *k* and around the inlet end of the exhaust port *i*. The gas passes from this chamber into the cylinder by an annular row of admission passages, nozzles *n* or orifices which preferably extend upwardly and outwardly, so as to direct the jets of gas against the inner surface of the cylinder.

The piston is preferably provided above these admission passages with an annular flange *m* overhanging the same and separated from the inner surface of the cylinder by a narrow annular space. This deflecting flange directs the annular row of streams or jets of gas outwardly and against the inner surface of the cylinder.

The annular gas admission device distributes the incoming fresh fuel circumferentially around the inner surface of the cylinder so that the fresh fuel forms an annular layer which lies closely against that surface and envelops the body of spent gases contained in the cylinder. The thickness of the annular layer of fresh fuel increases quickly as the gas rushes into the cylinder and the fresh fuel drives the spent

gas inwardly, toward the axial portion of the cylinder and out through the axial exhaust port *i* of the piston. By this means the cylinder is quickly scavenged or freed 5 from the spent gases and the mixing of the fresh fuel with the spent gases is reduced to a minimum.

I claim as my invention:

1. The combination with a cylinder having a fuel inlet port, of a piston having a fuel distributing chamber therein adapted to communicate with said port, and an annular series of fuel admission passages extending outwardly from said chamber and 10 arranged to discharge adjacent to the periphery of the piston, substantially as set forth.
2. The combination with a cylinder, having a fuel inlet port, of a piston having a fuel distributing chamber therein adapted to communicate with said port, an annular series of fuel admission passages extending from said chamber toward the periphery of the piston, and an annular deflecting 25 flange extending toward the wall of the cylinder over said passages, substantially as set forth.
3. The combination with a cylinder having a fuel inlet port and an exhaust port arranged to be uncovered by the piston 30 when it is near the limit of the power stroke, of a piston having an exhaust port therein, a fuel distributing chamber arranged in said piston between said exhaust port and the 35 periphery of the piston, and an annular series of fuel admission passages which extend from the said chamber toward the periphery of the piston, substantially as set forth.
4. The combination with a cylinder having a fuel inlet port and an exhaust port arranged to be uncovered by the piston when it is near the limit of the power stroke, of a piston having an exhaust port therein, a fuel distributing chamber in said piston 45 surrounding said exhaust port, an annular series of fuel admission passages extending from said chamber toward the periphery of the piston, and an annular deflecting flange 50 extending toward the periphery of the piston over said passages, substantially as set forth.
5. In a two-cycle internal combustion engine, an internally chambered cylinder; a reciprocating piston arranged within the cylinder-chamber; a fuel-conducting port 55 formed in the periphery and extending circumferentially of the piston, and opening into the cylinder-chamber at and circum-

ferentially of the face of the piston, the 60 forward portion of the said port having a laterally and outwardly facing side wall which is substantially parallel with the line of movement of the piston, said port being enlarged at the inner end of the said wall 65 inwardly toward the center of the piston and the enlarged portion of the port having a laterally and outwardly facing side wall which slopes laterally outwardly and toward the face of the piston and connects 70 with the first-mentioned wall; means for supplying fuel to the said port, and means for exhausting the cylinder.

6. In an internal combustion engine, a piston having a front of hollow character 75 provided with an inner circular flange fitting closely in the cylinder and an outer flange separated from the said inner flange by an interval, said outer flange extending circumferentially of the piston and spaced 80 from the adjacent piston-surrounding portion of the cylinder, said front having an opening formed at and centrally of the face of the piston; an exhaust-port formed in the said front and communicating with the 85 said opening, which exhaust-port registers with an exhaust-passage leading from the cylinder when the piston is at the lower end of its stroke, and inlet passages formed in the cylinder and communicating with the 90 aforesaid interval between the aforesaid flanges when the piston is at the lower end of its stroke.

7. In an internal combustion engine, a piston having a front of hollow character 95 provided with an inner circular flange fitting closely in the cylinder and an outer flange separated from said inner flange by an interval, said outer flange extending circumferentially of the piston and spaced 100 from the adjacent wall or walls of the cylinder, said front having an opening in its top; exhaust-ports below the face of the piston and communicating with the said opening and registering with exhaust-pas- 105 sages leading from the cylinder when the piston is at the lower end of its stroke, and inlet passages formed in the cylinder walls and communicating with the aforesaid interval between the aforesaid flanges when 110 the piston is at the lower end of its stroke.

Witness my hand this 14th day of August, 1906.

HERBERT McCORNACK.
